UNITED STATES PATENT OFFICE.

TIMOTHY J. BURKE, OF MIDDLETOWN, NEW YORK.

HAT AND CAP HOLDER.

1,154,371.

Specification of Letters Patent. Patented Sept. 21, 1915.

Application filed February 2, 1914. Serial No. 815,893.

To all whom it may concern:

Be it known that I, TIMOTHY J. BURKE, a citizen of the United States of America, and a resident of Middletown, Orange county, 5 and State of New York, have invented certain new and useful Improvements in Hat and Cap Holders, of which the following is a specification, reference being had to the accompanying drawings, forming a part 10 thereof.

My invention relates to spring clamp holders for caps, coats, programs, and other articles, and has special reference to such devices as are adapted to be attached to the 15 backs of seats or pews in theaters, churches and other public auditoriums as well as for household and office use.

One object of my invention is to provide a simple and inexpensive device of the afore- 20 said character that shall be reliable in operation and embodying a number of important detailed improvements, with a view to overcoming the disadvantages which have prevented the extensive use of such devices of 25 this class which have been hitherto devised.

Other objects and advantages of my invention will be set forth hereinafter, and in order that my invention may be thoroughly understood, I will proceed to describe the 30 same in the following specification, and then point out the novel features thereof in appended claim.

Referring to the drawings: Figure 1 is a front elevation of a spring clamp holder constructed in accordance with my invention. 35 Fig. 2 is a central sectional elevation on the line 2—2 of Fig. 1. Fig. 3 is a perspective view of the clamp in use, it being shown in position on a supporting surface to which it 40 is secured.

The clamp illustrated is composed of a single strip of resilient sheet metal formed to comprise a spring arch clip A, and a spring ring B which forms a continuation 45 of the arch at one end. The arch at the opposite end is bent at C in order that it may lie flat against a supporting surface such for example as the surface X shown in Fig. 3. The ring B has a single screw hole E which 50 is offset toward the arch from the point of tangency of the ring with a plane supporting surface when the device is not under tension.

The free end of the ring is bent back on 55 itself to form a short radius curve at K in

order that the end of the strip may be protected by the adjacent surface of the ring B.

When the device is secured to a surface such as X, by a single screw Y, which extends through the hole E, the device is 60 placed under tension by reason of the offset position of the hole E since the tightening of the screw serves to rotate slightly the ring B, and flatten the arch A to some extent.

Special attention is directed to the fact 65 that there are no exposed ends or hooks upon which the clothing of persons passing into and out of a seat, may catch. Furthermore, by reason of the fact that only a single screw is employed, the holder may readily be 70 mounted in any desired position, no special tools or skilled labor being necessary.

The device is utilized for supporting various articles as indicated in Fig. 3. For example, a program M may be mounted at 75 the top of the clamp, a cap H supported by the spring ring B, and gloves G supported under the end of the arch A. The device may of course be used for supporting various other articles as, for example, a cane or umbrella, and in fact it may be utilized in an entirely different connection for supporting records, bills, reports and other papers. It may also be utilized for supporting towels, 80 newspapers and various other articles. 85

My invention is not restricted to any particular class of surface and may obviously be employed in a wide variety of different connections, and I intend only such limitations as are imposed by the appended claim. 90

What I claim is:

A device of the character described, composed of a single strip of resilient sheet metal formed to comprise a spring arch clip adapted to be mounted on a plane supporting surface with one end lying flat against the surface, a spring ring forming a continuation of the arch at the other end and having a hole offset toward the arch from the point of tangency between the ring and the supporting surface, whereby an attaching screw extending through the hole tends to flatten the arch and place the clip under tension. 95 100

In witness whereof, I have hereunto set my hand in the presence of two subscribing 105 witnesses, this 31st day of January, 1914.

TIMOTHY J. BURKE.
